DESIGN FOR A CABLE HOLDER

Taft H. Harris, Portland, Oreg., assignor of one-fifth to Bufor Harris, one-fifth to Howard H. Harris, one-fifth to Franklin D. Harris, and one-fifth to Raymond W. Harris, all of Portland, Oreg.

Application January 27, 1944, Serial No. 112,349

Term of patent 7 years

(Cl. D26—1)

To all whom it may concern:

Be it known that I, Taft H. Harris, a citizen of the United States, residing at Portland, in the county of Multnomah and State of Oregon, have invented a new, original, and ornamental Design for a Cable Holder, of which the following is a specification, reference being had to the accompanying drawing, forming part thereof.

I claim:

The ornamental design for a cable holder, as shown.

TAFT H. HARRIS.
